UNITED STATES PATENT OFFICE.

ELIE FORMAN, OF BOSTON, MASSACHUSETTS.

CAP.

No. 873,122.

Specification of Letters Patent.

Patented Dec. 10, 1907.

Application filed July 13, 1906. Serial No. 326,095.

To all whom it may concern:

Be it known that I, ELIE FORMAN, a citizen of the United States, residing at Boston, county of Suffolk, and State of Massachusetts, have invented an Improvement in Caps, of which the following description, in connection with the accompanying drawing, is a specification, like letters on the drawings representing like parts.

10 This invention relates to caps and has for its object to provide a cap having the novel features which will be more fully hereinafter described and then pointed out in the claims.

In the drawings, Figure 1 is a perspective view of a cap embodying my invention; Fig. 2 is an enlarged view of the cap shown partly in vertical section to better show the construction; Figs. 3, 4 and 5 show different steps in the process of making the cap, and 20 Fig. 6 is an enlarged section through the foundation of the cap at the front portion thereof.

The cap comprises a foundation, a band surrounding the foundation and secured thereto at its upper edge for the entire distance around the cap, and at its lower edge through a portion of the distance around the cap, a top or body which is secured to the upper edge of the band and the foundation, 30 and a lining for the top, the edge of which overlies and is secured to the upper edge of the foundation.

3 Designates the foundation which may be of any suitable material, such as card-board 35 or leather-board in the form of a band of proper height to form the side of the cap; 4 the band which surrounds the same; 5 the top; 6 the lining of the top; 7 the sweat-band, and 8 the vizor.

40 In making the hat according to my invention, I take a body-band 3 of suitable material and first apply thereto the band 4 which is preferably of the same height as the body-band and which constitutes a portion of the

45 outside of the cap. This band 4 is for a portion of its length folded around under the lower edge of the foundation 3, as shown at 9 Fig. 3, and is sewed thereto by suitable stitching 10. The sewing 10 extends en-

50 tirely around the cap except the portion occupied by the vizor 8. At this portion, the band 4 is disconnected from the foundation 3 at the lower edge thereof. The upper edge of the band 4 may or may not be sewed directly to the foundation as desired. The next step in the process is the securing of the

body or top 5 to the foundation and band 4. This is accomplished by first turning the foundation with the band applied thereto wrong side out, and then turning the body 5 wrong side out and laying the outer side thereof against the inner side of the turned foundation, as shown in Fig. 4; that is, against the band 4 which will be the outer side when the cap is turned right side out again, and then securing said body 5 to the band 4 and the foundation by means of suitable stitching 11.

In the manufacture of the body 5, it is provided with a suitable lining 6, and the lining is made longer than the body 5, so that a flap or portion 12 of the lining extends down below the lower edge of the body. For securing the body to the foundation, the flap 12 is turned back, as shown in dotted lines Fig. 4, 75 so that the stitching 11 passes through the body 5 and foundation and band 4 only. Thereafter the flap 12 is turned around over the upper edge of the foundation, as shown in full lines Fig. 4, and is sewed thereto by 80 suitable stitching 13. The cap is then turned right side out and the top and foundation and band 4 have the arrangement and appearance shown in Fig. 2. The sweat-band 7 is then secured in place by suitable stitching 16, 85 and as the last step in the manufacture of the hat, the vizor 8 is secured in place. In attaching the vizor, the upper edge thereof is inserted beneath that portion of the lower edge of the band 4 which is disconnected 90 from the foundation 3, as shown in Fig. 2, and after the sweat-band has been turned down out of the cap, the vizor is sewed to the foundation by suitable stitching 15. Previously to this the portion of the foundation 95 against which the vizor abuts has had a facing strip 14 applied thereto, as seen in Fig. 6, this facing strip forming a finish for the lower edge of the foundation at the point where the vizor is situated.

A cap embodying my invention has the upper edge of the foundation secured directly to the body and the flap 12 of the lining constitutes a finish for the upper edge of the foundation, thus avoiding the necessity of 105 sewing in place any special facing strip for a finish.

Having fully described my invention, what I claim as new and desire to secure by Letters Patent is:—

1. In a cap, an annular foundation member, a finishing band surrounding the foun-

100

110

dation and secured thereto, and a top having its lower edge secured directly to the upper edge of the foundation, said top overhanging the foundation member and having a lining, 5 the lower edge of which is folded over and secured directly to the top edge of the foundation and thus constitutes a finish therefor.

2. In a cap, a foundation, a band surrounding the foundation and secured thereto, a top 10 of a size to overhang the foundation and having its lower edge secured directly to the upper edge of the foundation, said top having a lining, the lower edge of which is folded over and secured to the top edge of the foundation 15 and constitutes a finish therefor, and a sweat-band secured to the lower edge of the foundation and overlying the folded-over edge of the lining.

3. In a cap, a foundation, a band surrounding the same and secured to the lower edge 20 thereof for a portion of its length, a top separate from the band and having its lower edge turned upwardly and lying against the upper edge of the band and secured to the band and 25 foundation by stitches, said top having a lin-

ing provided with a flap which is folded over the upper edge of the band and foundation and secured thereto by stitches, and a sweat-band secured to the lower edge of the foundation and overlying the folded-over portion of 30 the lining.

4. In a cap, an annular foundation member of stiff material, a finishing band surrounding the foundation member and secured thereto, and a top overhanging the foundation member 35 and having its lower edge turned upwardly and secured to the outer side of the top edge of the foundation member, said top having a lining, the lower edge of which is folded over the top edge of the foundation 40 and is secured both to the inner and outer sides thereof.

In testimony whereof, I have signed my name to this specification, in the presence of two subscribing witnesses.

ELIE FORMAN.
